(57) **CLAIM**

The ornamental design for a safety blood collection holder, as shown and described.

DESCRIPTION

FIG. 1 is a perspective view of my new invention showing a safety blood collection holder having an internal container inserted into an external container;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front view showing the safety blood collection holder of FIG. 1. in an alternate position with the internal container partially removed from the external container;

FIG. 9 is a perspective view thereof;

FIG. 10 is a front view showing the external container of the safety blood collection holder of FIG. 1. with the internal container removed therefrom for clarity; and,

FIG. 11 is a front view showing the internal container of the safety blood collection holder of FIG. 1. having been removed from the external container for clarity.

FIGS. 1-11 illustrate a single embodiment of the invention with the parts being separated in FIGS. 10 and 11 for clarity.
